Barlow & Barber
ATTORNEYS.

UNITED STATES PATENT OFFICE.

ALEXANDER EKLUND, OF ATTLEBORO, MASSACHUSETTS, ASSIGNOR TO GENERAL CHAIN COMPANY, OF PROVIDENCE, RHODE ISLAND, A CORPORATION OF MASSACHUSETTS.

STRAP HOOK.

Application filed September 10, 1926. Serial No. 134,680.

This invention relates to a device for connecting the end of a flexible strap to a bar or bail member, more particularly of the type for attaching the end of a flexible bracelet strap to the bail of a wrist watch; and the object of this invention is to provide a simple and practical construction of such a device having a hook which may be releasably connected to a bail member and to which the end of a flexible strap may be releasably attached by a clamp or the like.

A still further object of the invention is to provide a connector of this type having a smooth under surface for engagement with the person of the wearer.

A still further object of the invention is to provide a clamping member for the end of a flexible strap which when in closed or gripping position also serves to completely close the opening to the hook to prevent the member engaged by the hook from moving from engagement with the same and from exerting an opening action on the closure member.

With these and other objects in view, the invention consists of certain novel features of construction, as will be more fully described, and particularly pointed out in the appended claims.

In the accompanying drawings:

Figure 1 is a side elevation of a wrist watch illustrating the improved connector as attaching the ends of a flexible bracelet strap to a wrist watch.

Figure 2 is a perspective view of the under side of the body member of the connector.

Figure 3 is a perspective view of the gripper or clamp which is pivoted therein.

Figure 4 is a top plan view of the body of the connector with the clamp removed or swung to open position.

Figure 5 is a bottom plan view of the complete device showing in dotted lines a bail member engaged by the hook.

Figure 6 is a sectional side view showing the connector in its operating position with the clamp engaging the flexible strap and the hook engaging the bail of a wrist watch.

Figure 7 is a side elevation partly in section showing the clamp in its open or released position.

Figure 8 is a central sectional elevation showing the clamp in a position intermediate its full open or closed position.

It is found in practice desirable to pro-

vide a hook for the end of a flexible strap and the like to which the strap may be releasably secured by a gripper or clamp, and it is also found desirable to form the clamp so that it will also completely close the hook of the body of the connector to prevent accidental disengagement of the hook from the member to which it is connected and also to provide a smooth surface on the under side of the hook for contact with the arm of the wearer when used for a wrist watch bracelet and it is further found desirable to provide teeth on the gripper which will so extend into the flexible member that the flexible member will not be completely disengaged from the gripper when the latter is swung to its open position thereby preventing inadvertent or accidental disengagement of the strap and a consequent dropping of the wrist watch or other member to which the same may be attached; and the following is a detailed description of one means by which these advantageous results may be accomplished:

With reference to the drawings, 10 designates a wrist watch having bail members 11 with a flexible strap 12 connected thereto by means of a connector or end hook 13. This connector comprises a body member having a base plate 14 with an extended hook-shaped portion 15 with side walls 16 turned inwardly as at 17 to lie spaced from and substantially parallel with the plate 14 and provided with a stop finger 18 to limit the insertion of the strap 12 into the body.

Between the side walls 16 and in the openings 19 is a clamp member 20 which is substantially L-shape in cross section. Teeth 21 are provided along one edge of the clamp and the portion carrying the teeth is extended laterally to form trunnions 22 which extend into the openings 19 to pivotally mount the clamp in the body. It will be seen that the stop finger 18 is positioned at a point remote from the pivotal mounting 19 of the clamp so that the strap will extend into the body a substantial extent to permit of a firm engagement of the clamp with the strap at a point removed from the end thereof.

Arms 23 carried by the free end of the clamp form a stop to limit the closing movement of the clamp and also form an extending of the side walls 16 to completely close the hook opening, as is illustrated in

Figure 6 and so prevent a movement of the bail 11 from beneath the hook and thus the bail cannot move to a position beneath the clamp 20 to cause accidental opening movement of the clamp relative to the body in which it is pivoted.

A notch 24 is provided in the edge of the hook 15 to permit the finger nail to be inserted beneath the sheet metal edge of the clamp 20 to swing the clamp to its open position, as illustrated in Figure 7. The clamp is limited in its opening movement by stops 25 which permit the clamp to swing only through an arc of substantially 90° to a position at substantially right angles to the body of the hook, as illustrated in Figure 7. In this open position in Figure 7, sufficient space is provided to permit of free insertion of the strap 12 into the body for gripping the same by a swinging of the clamp to the closed position as illustrated in Figure 6. The teeth 21 of the clamp are bent inwardly toward the hook slightly to better resist the tension on the strap in the direction of the arrow in Figure 6, and also the points of the teeth so penetrate into the strap as to remain in the strap slightly even when the clamp is swung to its open position thereby preventing a complete disengagement of the strap and the teeth.

In order to completely disengage the teeth of the clamp from the strap, it is only necessary to throw the lever back to its wide open position and then move the strap endways inwardly, which action serves to withdraw the teeth from engagement with the surface of the strap and permits its free removal from the clamp.

It will be noted that the clamp is so arranged that any strain in the direction of the arrow, in Figure 6, tends to move the clamp to closed position rather than to open the same and that the clamp is so constructed that the surface of the end of the hook of the body and the clamp when closed, is substantially flush to be smooth to the arm of the wearer of a wrist watch and prevents abrading of the flesh.

In some instances, the edges 26 of the arms 23 may frictionally engage the forward edge of the flanges 17 and fingers 18, if desired, whereby the clamp member 20 will be caused to snap into place when closed and so retain it against accidental opening.

It will be apparent that this hook has

uses other than for a wrist watch strap and may be used for any purpose for which it is adapted such as for a body belt garter or the like.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A connector for the end of a flexible strap, comprising a body member having a hook-shaped portion, a strap clamp pivoted in said body to swing to open position to permit entry of the strap beneath it, and a stop carried by said body positioned at a point remote from the pivotal mounting of the clamp to engage the end of the strap and limit its insertion beneath said clamp. 70

2. A connector for the end of a flexible strap, comprising a body member having a hook-shaped portion, a strap clamp pivoted in said body and having a portion for completely closing the entering opening to said hook-shaped portion when said clamp is in strap gripping position, and side arms carried by said clamp for limiting its closing movement thereof, said side arms being positioned to lie flush with the sides of said body and prevent the member engaged by the hook from moving from beneath the hook. 80 85

3. A connector for the end of a flexible strap, comprising a body member having a hook-shaped portion with an arc-shaped notch in its edge and a strap clamp pivoted in said body and having its end lying flush with the end of the hook-shaped portion. 90 95

4. A connector for the end of a flexible strap comprising a body member having a base plate, side walls formed on the base plate, portions turned inwardly from the side walls lying parallel to and spaced from the base plate, a hook carried by the body, a strap clamp pivoted in the side walls of said body to swing into and out of engagement with the strap, and a stop carried by said body clamp to engage the inturned portion of said side walls to limit the opening movement of the clamp. 100 105

In testimony whereof I affix my signature.

ALEXANDER EKLUND.
